CLAIM

The ornamental design for a lug for a bicycle frame for connecting seat tube to top tube, as shown.

DESCRIPTION

FIG. 1 is a perspective view of a lug for a bicycle frame for connecting seat tube to top tube showing our new design;

FIG. 2 is a top plan view thereof;

FIG. 3 is a right side elevational view thereof;

FIG. 4 is a left side elevational view thereof;

FIG. 5 is a bottom plan view thereof;

FIG. 6 is a front elevational view thereof; and,

FIG. 7 is a rear elevational view thereof.

FIG. 1

FIG. 4

FIG. 2

FIG. 3

FIG. 5

FIG. 6

FIG. 7
